UNITED STATES PATENT OFFICE

159,878

DECK OF PLAYING CARDS

Josephine M. Whiting, Washington, D. C.

Application July 28, 1948, Serial No. 147,807

Term of patent 14 years

(Cl. D34—13)

To all whom it may concern:

Be it known that I, Josephine M. Whiting, a citizen of the United States, and a legal resident of Massachusetts, residing at 2018 F Street, N. W., Washington D. C., have invented a new, original, and ornamental Design for a Deck of Playing Cards, of which the following is a specification, reference being had to the accompanying drawings, forming part thereof:

Figs. 1-4 inclusive are face views of the kings in my pack of playing cards.

Fig. 5 is a face view of the joker card thereof.

Figs. 6-9 inclusive are face views of the queens in my pack of playing cards.

Figs. 10-13 inclusive are face views of the jacks in my pack of playing cards.

Figs. 14-23 inclusive are face views of the aces and spot cards comprising the remainder of the deck, each figure being illustrative of four identical cards.

The top half of the face card not shown in Fig. 1 is identical to the bottom half therein.

The deck of playing cards consists of two or more jokers and four suits of thirteen cards designated by four colors, the aces and spot cards differing only as to color. The backs are conventional.

I claim:

The ornamental design for a deck of playing cards, as shown and described.

JOSEPHINE M. WHITING.
